PUMP

Torbjörn Viktor Dillström, Stockholm, Sweden,
assignor to Handelsaktiebolaget Vidar, Stockholm, Sweden, a corporation of Sweden

Application August 10 1938, Serial No. 224,214
In Sweden September 28, 1937

13 Claims. (Cl. 123—139)

The present invention relates to plunger pumps and has particular reference to plunger pumps particularly adapted to deliver liquid fuel under pressure for injection to different cylinders of an internal combustion engine. Still more particularly the invention relates to pumps of the above character from which fuel is separately delivered to different pump outlets from a common pump chamber at different times during one delivery stroke of the pump plunger.

In the operation of internal combustion engines to which fuel is injected it is frequently desirable, when the engine is operating at low load or no load, to operate on less than the total number of cylinders, cutting out certain of the cylinders in order that remaining cylinders may be operated under more favorable combustion conditions than if the small amount of fuel required to carry the low or idling load were distributed between all of the cylinders of the engine.

The present invention has for its general object the provision of an improved form of plunger pump construction of the kind in which a plurality of pump outlets are supplied with fuel from a common pump cylinder at different times during one delivery stroke of the pump plunger, and in which the delivery of liquid to one or more of the pump outlets may be cut out at will, without affecting the delivery of liquid to others of said outlets. Other and more detailed objects of the invention and the manner in which it may be carried into effect will best be understood from a consideration of the ensuing portion of this specification in which several practical examples of pump construction embodying the invention are described by way of illustration, reference being had to the accompanying drawings, in which:

Fig. 1 is a central section of a pump embodying the invention and adapted to supply liquid to four outlets from a single pump cylinder;

Fig. 2 is a section taken on the line 2—2 of Fig. 1;

Fig. 3 is a view taken on the line 3—3 of Fig. 2;

Fig. 4 is a developed view showing the cylinder and plunger porting of the pump illustrated in the preceding figures;

Fig. 5 is a more or less diagrammatic view illustrating apparatus suitable for effecting cut out of some of the outlets of the pump shown in Fig. 1;

Fig. 6 is a fragmentary section illustrating the

variation of a part of the pump construction shown in Fig. 1;

Fig. 7 is a fragmentary section showing a control valve of Fig. 6 in a different position;

Fig. 8 is a more or less diagrammatic sectional view illustrating still another variation of structure for effecting the cut out of certain of the pump outlets; and

Fig. 9 is a fragmentary section showing the valve of Fig. 8 in another position.

Referring now to Figs. 1 to 4, the pump illustrated comprises a main casing part 10 and a head part 12. A pump cylinder 14 is secured to part 12 by means of a suitable threaded collar 16 and a plunger 18 is reciprocably and turnably mounted in the bore of the pump cylinder. Pump chamber 20 is provided at the inner end of the plunger and liquid is drawn into this chamber through the suction line 22 under control of the spring loaded suction valve 24.

Plunger 18 has a foot 18a at its outer end which rests against the bottom of a cylindrical recess formed in the upper portion of a tappet 26 slidably mounted in the casing part 10 and having a roller 28 contacting the face of cam 30. The cam is carried by a cam shaft 32 mounted in suitable bearings 34 in the pump casting. An arcuate sector 36 mounted for turning movement in the pump casing around the tappet is provided with external teeth 38 located to engage teeth on a rack 40 slidably mounted in the casing and adapted to be actuated by any suitable control (not shown). Tappet 26 is prevented from turning in the casing by means of locating pin 42 fixed in the pump casing and at its inner end engaging a vertical slot 44 in the wall of the tappet. The pump plunger is caused to turn with the sector 36, when the position of rack 40 is shifted, by means of the pin 46 fixed at one end in the foot 18a of the plunger 40 and extending through an arcuate slot 48 in the wall of the tappet to engage a vertical slot 50 formed in the sector 36.

The pump spring 52 is compressed between the pump cylinder or barrel 14 and a spring retaining washer 54 seating against the tappet and serving also to engage the foot of the pump plunger to retain it in contact with the tappet. Spring 52 operates to cause the pump plunger and tappet to follow a path of reciprocation 50 determined by the profile of cam 30.

The pump cylinder is provided with a series of delivery ports d_1 , d_2 , d_3 , and d_4 each located at a different height in the pump cylinder. The ports are conveniently disposed in two axial 55

planes at 90° with respect to each other, as shown in Figs. 1, 2 and 3, but other dispositions of the ports peripherally of the bore may be employed. Ports d_1 — d_4 communicate respectively with delivery passages 56, 58, 60 and 62, which in turn communicate respectively with pump outlets 64, 66, 68 and 70, which as will be observed from Figs. 1 and 2, are advantageously distributed symmetrically around the central inlet 22. Each of the delivery passages communicates with its respective pump outlet through a spring loaded delivery valve 72 all of which valves are designated by the same reference character.

In order to provide for the location of the delivery ports in the two axial planes indicated in Figs. 1 and 2, while at the same time having the symmetrical distribution of the outlets, the portions of the delivery passages 60a and 62a in the pump cylinder, with which ports d_3 and d_4 communicate respectively, are brought into communication respectively with the passages 60 and 62 in the head of the pump by the respective connections 60b and 62b formed in the upper face of the pump barrel, as will be seen more clearly from Fig. 3.

As will be observed from Fig. 2, a series of relief or overflow ports r_1 , r_2 , r_3 and r_4 are arranged in vertical alignment in the pump cylinder, there being one overflow port at the same level in the pump barrel as that of each delivery port. These relief ports communicate through suitable transverse channels with a common relief or overflow passage 74 which, in the embodiment shown, delivers to a main overflow 76. Conveniently, the line of overflow ports is in the same axial plane as the delivery ports d_3 , d_4 ; port r_2 being directly opposite d_2 and port r_4 being directly opposite port d_4 .

The pump cylinder is further provided with additional overflow ports which may be conveniently termed auxiliary overflow ports. In the present embodiment two such ports are shown at a_1 and a_2 in Fig. 1 and these ports are conveniently located in the same axial plane with and opposite delivery ports d_1 and d_3 . Ports a_1 and a_2 communicate through suitable transverse channels with a common auxiliary overflow passage 78 leading to the auxiliary overflow 80 by way of an auxiliary overflow control valve 82 which in the embodiment illustrated is in the form of a plug-type valve adapted to be turned to open or close the auxiliary overflow passage 78.

Intermediate its ends the plunger 18 is provided with a circumferentially extending recess 84 which is constantly in communication with the pump chamber 20 by way of passage 86 in the plunger. An island-like control projection 88, the outer surface of which is in contact with the wall of the cylinder bore, is provided with an inclined control edge 90.

As will be seen from the developed view in Fig. 4, certain portions of the recess 84, indicated at 92, provide what may conveniently be termed plunger overflow ports which are in line with the rows of cylinder delivery ports d_1 , d_3 and d_2 , d_4 , respectively. Channels formed between the upper and lower edges of the projection 88 and the upper and lower edges respectively of the recess 84, provide at 94 and 96 two axially spaced ports in line with the row of main overflow ports r_1 — r_4 . The ports 94 and 96 may conveniently be considered as plunger overflow ports. The recess 84 further provides an auxiliary plunger overflow port, constituting that portion of the re-

cess which is in line with the row of auxiliary overflow ports a_1 and a_2 .

The operation of the pump above described is as follows: assuming valve 82 to be closed as indicated in Fig. 1, and it further being assumed that the pump chamber is full of liquid and the plunger ascending on its delivery stroke. In the position of the plunger shown in Fig 4, delivery port d_1 and auxiliary overflow port a_1 are both in communication with the plunger recess and the plunger overflow port 94 is in communication with the overflow port r_1 . As the plunger ascends from this position, delivery through port d_1 will not take place until port 94 passes out of communication with port r_1 , whereupon delivery through port d_1 will commence since flow through port a_1 is blocked by valve 82. The delivery period through port d_1 , which may constitute an injection period to a fuel injector, continues until port 96 comes into registry with port r_1 to terminate delivery flow through port d_1 . By the time this occurs, the plunger delivery port is in communication with port d_2 and before port 96 passes out of communication with port r_1 , port 94 is in communication with port r_2 to permit continuous overflow from the pump cylinder during the period between the time when delivery through port d_1 is cut off by registry of port 96 with port r_1 and the time when delivery through port d_2 is established by port 94 passing above and out of communication with port r_2 , port 96 having previously passed port r_1 . The above cycle of events takes place sequentially with respect to delivery through ports d_3 and d_4 as the plunger completes its delivery stroke, and, as was the case when delivery took place through port d_1 , delivery through port d_3 will take place in spite of communication between the plunger recess and the auxiliary overflow port a_2 , because of the fact of valve 82 being closed.

If now for any reason such as idling engine operation, it is desired to deliver through less than the total number of pump outlets, valve 82 is opened and by reference to Fig. 4 it will be apparent that with this valve open, delivery through ports d_1 and d_3 will not take place, since when the corresponding normal overflow ports r_1 and r_3 are covered by the control projection 88, overflow will take place through port a_1 , or port a_2 as the case may be, during the period when the plunger overflow port is passing port d_1 or port d_3 .

It will be apparent that the number and sequence of the delivery outlets that may be put out of action through the medium of the auxiliary overflow may be varied as desired by varying the number and longitudinal location of the auxiliary overflow ports. Ordinarily, when a pump of this kind is utilized as a fuel injection pump for an internal combustion engine, half the total number of pump outlets are arranged to be selectively put out of action by the auxiliary overflow ports and the auxiliary overflow ports are advantageously arranged as shown to put alternating delivery outlets out of action in order to provide equal time intervals between the remaining delivery periods.

In the drawings the pump plunger has been shown in the position of rotation corresponding to full load operation giving the maximum length of injection period through the ports through which delivery is effected. From inspection of Fig. 4 it will be apparent that if the plunger is turned so as to shift the control projection to the

right as viewed in this figure, to bring the control edge 90 in line with the overflow ports r_1-r_3 , the period of injection through each delivery port will be shortened. It will further be apparent that whether the plunger is in a position of rotation to effect either full or part load delivery through the various delivery ports, opening of the auxiliary overflow passage will have no effect on the length of the delivery periods determined by the position of rotation of the plunger and effected through the outlets which are not put out of action by the auxiliary overflow.

While for convenience of illustration, in order to bring the various cylinder ports into the planes of the several sections, these ports have been shown as distributed 90° apart around the circumference of the cylinder bore, from inspection of Fig. 4 it will be evident that ports d_1-d_4 and ports a_1, a_2 may be placed in any desired relation peripherally of the cylinder bore so long as they are peripherally displaced from the path of travel of the control projection 88 which cooperates with the line of overflow ports r_1-r_4 . In some instances it may be desirable to space the cylinder delivery ports and the auxiliary overflow ports so as to provide a greater peripheral distance for turning movement of the control projection, without interference with these ports, than is possible with the port distribution shown in Fig. 4.

Referring now to Fig. 5, there is illustrated more or less diagrammatically a convenient means for actuating the auxiliary overflow valve 82 to automatically cut certain cylinders of an engine out of action under predetermined engine operating conditions. In this figure the engine is indicated at 100, the air intake being indicated at 102. Control of the output of the engine is effected by means of the throttle valve 104 which through the control rod 106 may be operated manually, by governor, or in any other desired manner.

The pump is provided with an electric solenoid 108, in an electric circuit adapted to be closed so as to energize the solenoid when the contacts 110 are closed by movement of the throttle to a predetermined low or idling load position. When the circuit is closed, the armature 112 of the solenoid is pulled downwardly from the position shown in the drawings against the action of the retracting spring 114 and through the medium of the control arm 116 operates to turn valve 82 to a position which opens the auxiliary overflow passage 78.

In Figs. 6 and 7 a variation has been illustrated in which an auxiliary overflow valve 82a provides communication between a delivery passage, which may for example be passage 60, and an auxiliary overflow passage 78a which returns fuel from passage 60 to the suction line 22 when valve 82a is moved to the position shown in Fig. 7. Evidently, as many outlets may be cut out of action as desired by the employment of auxiliary overflow means of this kind.

In Figs. 8 and 9 there is shown more or less diagrammatically another form of construction for cutting out the delivery to any desired outlet. In this embodiment the delivery passage, for example passage 60, has interposed therein a piston valve 118 having two spaced recesses 120 and 122 therein. These recesses are connected by means of an internal passage 124 in the valve and an auxiliary overflow passage 78b communicates with the bore in which the valve member 75 slides. The valve is urged to the position shown

in Fig. 8 by a spring 126 and is moved to the position shown in Fig. 9, in the embodiment illustrated, by means of a piston 128 operating in cylinder 130 and loaded by spring 132. Cylinder 130 is ported at 134 to expose the face of the piston opposite spring 132 to atmospheric pressure and on the spring side of the piston the cylinder is provided with a connection 136 adapted to be connected to the air intake of the engine on the engine side of the throttle valve controlling air admission. In the position of the device shown in Fig. 8 it will be evident that delivery will take place through passage 60 since the pressure liquid cannot escape from the recess 122 to which it flows through the valve passage 124. If because of reduced air pressure in the connection 136 and the left hand portion of cylinder 130, due to throttling of the air supply to the engine, piston 128 is moved to the left to shift valve 118 to the position shown in Fig. 9, it will be evident that the delivery passage 60 will be placed in communication with auxiliary overflow passage 78b by way of recesses 120 and 122 and the valve passage 124, thus operating to cut out of action the outlet to which passage 60 delivers.

It will be evident that any suitable form of control may be used to actuate the different forms of auxiliary overflow valve construction described above as, for example, by employing manual control or electric solenoid control for the forms shown in Figs. 6 to 9 or employing the vacuum control for the arrangement shown in Fig. 5.

From the foregoing description it will be apparent that the invention may be carried into effect with numerous different specific forms of apparatus and it is accordingly to be understood as not limited in its scope to the forms herein described and illustrated by way of example, but is to be considered as embracing all forms of apparatus falling within the terms of the appended claims when they are construed as broadly as is consistent with the state of the prior art.

Certain specific features of the pump mechanism shown but not claimed, in this application, forms the claimed subject matter of my copending application Serial No. 224,211.

What I claim is:

1. A plunger pump constructed to effect delivery from a common chamber to different pump outlets at different times during the delivery stroke of the plunger, and means selectively operable to confine delivery to less than the total number of said outlets.

2. A plunger pump constructed to effect delivery from a common chamber to different pump outlets at different times during the delivery stroke of the plunger, means for adjusting the pump to vary in like manner the quantities delivered to the several outlets, and means selectively operable independently of the adjusting means to confine delivery to less than the total number of said outlets while permitting delivery to the remainder of quantities determined by the position of the adjusting means.

3. A plunger pump constructed to effect delivery from a common chamber to different pump outlets in sequence during the delivery stroke of the plunger, and means selectively operable to confine delivery to a number of outlets less in number than the total number and not in immediate sequence.

4. A plunger pump constructed to effect delivery from a common chamber to different pump outlets in sequence during the delivery stroke of the plunger, and means selectively operable to

confine delivery to every other outlet in the sequence.

5. A plunger pump having a plurality of outlets, means for effecting delivery to different outlets at different delivery periods during the delivery stroke of the plunger, overflow means for determining the times of said delivery periods, and auxiliary overflow means selectively operable to determine the number of ineffective delivery

10 periods during the delivery stroke of the plunger.

6. A plunger pump having a plurality of outlets, means for effecting delivery to different outlets at different delivery periods during the delivery stroke of the plunger, adjustable overflow

15 means for determining the timing and length of duration of the delivery periods and auxiliary overflow means selectively operable independently of said adjustable overflow means to determine the number of ineffective delivery periods during

20 the delivery stroke of the plunger.

7. A plunger pump including a cylinder having a plurality of longitudinally spaced delivery ports and a plurality of longitudinally spaced overflow ports, a ported plunger operable to effect delivery through different of said delivery ports at different times during the delivery stroke of the plunger, means providing for overflow from the pump, and means for selectively permitting or preventing overflow through the first mentioned means to respectively cut off or effect delivery through certain of said delivery ports.

8. A plunger pump including a cylinder having a plurality of longitudinally spaced delivery ports, a plurality of longitudinally spaced overflow ports and an auxiliary overflow port, a ported plunger operable to effect delivery through different of said delivery ports at different delivery periods during the delivery stroke of the plunger and to effect overflow through said overflow ports during the times intervening between the delivery periods, said auxiliary overflow port being located to be in communication with the pump chamber through said ported plunger during the time when delivery is normally effected through at least one of said delivery ports, and a valve for selectively permitting or preventing overflow through said auxiliary overflow port.

9. A plunger pump including a cylinder having a plurality of longitudinally spaced delivery ports, a plurality of longitudinally spaced overflow ports and auxiliary overflow means including a plurality of longitudinally spaced auxiliary overflow ports, a ported plunger operable to effect delivery through different delivery ports at different delivery periods during the delivery stroke of the plunger and to effect overflow through said overflow ports during the times intervening between the delivery periods, and valve means for selectively permitting or preventing overflow through said auxiliary overflow ports, said auxiliary overflow ports being located in the

cylinder so as to be placed in communication with the pump chamber through the ported plunger only at times when the plunger is in position to effect delivery through non-adjacent delivery ports.

10. A plunger pump including a cylinder having a plurality of longitudinally spaced delivery ports each connected to a different pump outlet, a ported plunger for placing different ports in communication with the pump chamber at different times during the delivery stroke of the plunger, a plurality of overflow ports located in the cylinder to determine the time and duration of delivery through said delivery ports, a plurality of auxiliary overflow ports in the cylinder, 15 said auxiliary overflow ports being located so that different ones thereof are placed in communication with the pump chamber by the ported plunger concurrently with different delivery ports respectively, and means for selectively preventing or permitting overflow through said auxiliary overflow ports.

11. A plunger pump including a cylinder having a plurality of longitudinally spaced delivery ports, delivery passages connecting each of said delivery ports to a different pump outlet, certain of said delivery passages having an overflow passage communicating therewith between the delivery port and the pump outlet, and valve means selectively operable to permit or prevent flow 30 through said overflow passages.

12. Fuel injection apparatus for multiple cylinder internal combustion engines comprising a pump including a cylinder and a cooperating plunger, a plurality of pump outlets receiving fuel 35 from the pump chamber at different times during the delivery stroke of the plunger and adapted to deliver the fuel to different engine cylinders respectively, overflow means for selectively preventing delivery from the pump cylinder to certain of said outlets, and means operable in response to a predetermined condition of engine operation for rendering said overflow means effective to prevent delivery to said certain of said pump outlets.

13. Fuel injection apparatus for multiple cylinder internal combustion engines comprising a pump including a cylinder and a cooperating plunger, a plurality of pump outlets receiving fuel from the pump chamber at different times 50 during the delivery stroke of the plunger and adapted to deliver the fuel to different engine cylinders respectively, overflow means for selectively preventing delivery from the pump cylinder to certain of said outlets, and means operable 55 in response to an impulse indicative of predetermined low or idling load operation of the engine for rendering said overflow means effective to prevent delivery to said certain of said pump outlets.

TORBJÖRN VIKTOR DILLSTRÖM.
